224,827

BOTTLE OR SIMILAR ARTICLE

Harry Kravitz, Wynnewood, Pa., assignor to Andorra Nurseries, Inc., Wynnewood, Pa.

Filed Apr. 8, 1971, Ser. No. 132,627

Term of patent 14 years

Int. Cl. D9—01

U.S. Cl. D9—47

FIG. 1 is a front elevation view of a bottle or similar article showing my new design;

FIG. 2 is a top plan view thereof;

FIG. 3 is a left side view thereof;

FIG. 4 is a right side view thereof; and

FIG. 5 is a bottom plan view thereof.

The rear elevation view is a mirror image of the front elevation view shown in FIG. 1.

I claim:

The ornamental design for a bottle or similar article, substantially as shown and described.
